United States Patent Office

Des. 226,324

Patented Feb. 13, 1973

226,324

TABLE LAMP

Giuseppe Longato, Via Makalle 19, Padova, Italy

Filed May 3, 1971, Ser. No. 139,990

Term of patent 14 years

Int. Cl. D26—05

U.S. Cl. D48—20 R

FIG. 1

FIG. 2

FIG. 3

FIG. 4

FIG. 5

FIG. 6

FIG. 1 is a perspective view of a table lamp showing my new design;

FIG. 2 is a side elevational view thereof;

FIG. 3 is a bottom plan view thereof;

FIG. 4 is a top plan view thereof;

FIG. 5 is a front elevational view thereof;

FIG. 6 is a rear elevational view thereof.

I claim:

The ornamental design for a table lamp, as shown and described.
